DISPENSING WINDOW

Albert G. Oakes, Houston, Tex.

Application August 31, 1953, Serial No. 377,602

4 Claims. (Cl. 20—4)

This invention relates to new and useful improvements in a dispensing window.

It is an object of this invention to provide a window for use in business establishments engaged in dispensing products to customers or waitresses on the outside of the building. This type of window is particularly adaptable to such business establishments as ice cream stands; hamburger stands and the like.

It is another object of the invention to provide a window that may be raised by the foot of the operator and locked in raised position without assistance from the hands of the operator, which may be engaged in handling the product being dispensed.

It is still another object of the invention to provide a window for food dispensing establishments that may be provided with interchangeable frames so that a screen may be quickly replaced with a glass and that may be locked in closed position in a novel manner.

With the above and other objects in view, the invention has relation to certain novel features of construction and operation more particularly set out in the following specification and illustrated in the accompanying drawings, wherein:

Figure 1 is a plan view, taken from the inside of the building in which the window is installed.

Figure 2 is a front elevational view, taken on the line 2—2 of Figure 1, with parts of the framework broken away.

Figure 3 is a side elevational view in cross section, taken on the line 3—3 of Figure 1.

Figure 4 is a front view of the table and window release lever taken on the line 4—4 of Figure 1, and

Figure 5 is a bottom view, partly in cross section, of the anchor block employed, taken on the line 5—5 of Figure 1.

Referring now more particularly to the drawings, the numeral 1 designates a supporting shelf mounted on the inside wall of a building, such as an ice cream vending stand, on which the channel shaped post members 2, 2 are mounted in an upright position. The post members 2, 2 are mounted with the projecting edges of the channel abutting each other, forming a hollow post, and are maintained in this position by means of suitable bolts as 3. Two posts are formed, but the construction of each post and the operating mechanism hereinafter described as being mounted in the posts are identical. Anchor blocks 4 are secured to the plate 5 and to the shelf 1 to align the posts 2, 2 in the desired position. A pair of guide bars 6, 6 are mounted on each inside face of the posts 2, 2 in which the window frame 7 is loosely mounted. A projection, as 8, extends upwardly from the frame 7 and is equipped with a cross bar 9. An S-shaped hook 10 is releasably secured to said cross bar 9 at one end and is secured to one end of the cable 11 at its other end. The cable 11 extends through the post 2, over a suitable pulley 12 and through the block 13, thence through the pulley 14, back through the block 13 and

is anchored to the pin 15 in the post 2. The pulley 14 is also anchored to the pin 15 in the post 2. The block 13 is secured to the cable 19 which extends from the block 13 through the pulley 15, through an opening in the post 2 and through the guides 17 and the roller 18 which are mounted on the horizontal foot members 45, 45, and is anchored to the hinged foot pedal 20. The above construction is duplicated, one set being on each side of the window and the foot pedal being formed by a bar connecting the two cables 19, 19.

A table extends through the opening between the posts 2, 2, and is anchored in any suitable manner as by the bolts 22, 22 and a channel shaped supporting beam 23 which extends transversely beneath the table 21 and is aligned by suitable anchor blocks as 24, which is in turn anchored to the posts 2, 2 by bolts as 25 which extend through one side of the posts 2 and into the strip 26. Suitable additional supports, as 39, 39, support the table 21 on the inside of the building. Channel shaped shoes 27, 27 are mounted on the edges of the plate glass 28. Suitable glass holding strips, 29, having means for receiving the hidden bolts 30, maintain the plate glass in place. The shoes 27, 27 are separated by suitable supporting beams 31, 31 which bear the weight of the plate glass above the window opening.

Beneath the table 21 may be mounted a suitable cash drawer as 32 and beneath the cash drawer 32 is mounted on the underside of the table 21 by means of the eye-bolts 34, 34, a lock release lever 33, which has an extension 35 extending beyond the edge of the table 21 and is readily available to the hand of the operator. A latch 36, preferably spring loaded, is mounted on the floor 37 of the building and is positioned to engage the foot pedal 20 when depressed by the operator and to hold the pedal 20 in lowermost position until it is released by the operator. A cable 38 extends from the lever 33 to the latch 36, and will raise the latch 36 out of engagement with the pedal 20 when the extension 35 is manipulated by the operator.

As shown in the drawings, the window is equipped with two frames, the first frame, 7, shown with a screen mounted in the framework, and which is positioned in the guides 6, 6. The other frame 40 is shown equipped with glass. When the establishment where the window is employed is in operation, the frame 40 will be maintained in a raised position, out of the way, and locked in raised position by means of the pin 41, which may be moved into locking position through suitable openings in either, or both, posts 2, 2, and the frame 7 may be locked in position to prevent unauthorized opening thereof by means of the pin 42 through the guides 6, 6; when it is desired to change the frames 7 and 40, the frame 7 is deactivated by disengaging the hook 10 from the cross bar 9 and raising the frame 7 and locking same in raised position by inserting the pin 42 through the guide bars 6, 6, beneath the frame 7, then removing the locking pin 41 from beneath the frame 40 and freeing the frame 40 for longitudinal movement between the outer guide 6 and the inside edge of one of the posts 2, and securing the hook 10 to the cross bar 43 of the frame 40. The frame 7 will thus be deactivated and the frame 40, operated by the cable 11, activated, thus placing the dispensing window back in operation with the frame 40 becoming the vertically movable frame.

In use, the operator, approaching the window, may open the window by depressing the foot pedal 20, and thus raise the vertically movable frame. The latch 36 will engage the pedal 20, maintaining same depressed and holding the frame in open position. The operator will thus be able to raise the frame while his hands are occupied such as with an order for a customer outside of the building; when the transaction is completed and

the operator's hands are no longer occupied, the frame may be quickly and easily lowered by depressing the pedal 20, releasing the latch 36 by means of manual manipulation of the lever 35, which, upon being depressed, lifts the locking means of the latch 36, by means of the cable 38, releasing the pedal 20 and the weight of the frame 7, or 40, will close the window by gravity. The operator may control the speed of lowering of the movable frame by riding the pedal with his foot, or any other suitable type of speed check may be employed.

It is contemplated that the posts of the hereinabove described device, as well as all other structural parts, will be manufactured from aluminum, or similar light-weight, durable material. The lower ends of the posts 2, 2 may be formed in separate sections, as 44, to permit mounting of the pulleys 16, and to provide the openings 45 in the posts through which the cables 19, 19 may operate; however, any desired method of mounting said pulley may be employed.

While the foregoing is considered a preferred form of the invention, it is by way of illustration only, the broad principle of the invention being defined by the appended claims.

What I claim is:

1. In a dispensing window, a pair of hollow posts, a horizontally extended table mounted between said posts, blocks suspended in said posts, a movable window and a stationary window interchangeably mounted between said posts, cables having one end secured to the upper portion of said movable window and their other ends to said blocks, a pedal pivotally mounted beneath said table, and cables connecting said blocks and pedal.

2. In a dispensing window, a pair of hollow rigid posts, means for mounting a pair of interchangeable window frames between said posts, one of said frames being movable vertically between said posts, a table mounted horizontally between said posts limiting the downward movement of said movable window frame, a cable detachably secured to said movable frame at one end, a block in each of said posts through which said cable passes the other end

of said cables being anchored in said posts, a pedal cable secured at one end to said block and a foot pedal pivotally mounted beneath said posts to which the other end of said pedal cable is secured.

3. In a dispensing window, a building having a ledge, ceiling and a plate, means for mounting plate glass between said ledge and ceiling, a window in said plate glass comprising, a pair of hollow posts, means for receiving plate glass molding on one margin of said posts, a rigid framework forming a dispensing window opening, window guide arms mounted on the inside faces of said posts, window frame having rigid margins mounted and maintained in vertically movable relation in said guide arms, a cable extending through said posts from above said window frame having window engaging means on one end and being secured to window elevating means inside of said posts at the other end, pedal operable means for raising and lowering said window frame.

4. In a dispensing window a framework having a pair of hollow posts, a table mounted horizontally between said posts, means for securing plate glass to the outer margins of said posts, a window opening framework between said posts, a pair of windows interchangeably mounted between said posts, one of said windows being releasably mounted in a fixed position and one of said windows being movable vertically between said posts, guide means on said posts for guiding the vertical movement of said movable window, and means operable through said posts for raising and lowering said movable window.
